UNITED STATES PATENT OFFICE.

CURTIS S. JORDAN, OF LOS ANGELES, CALIFORNIA.

TIMER.

1,354,655.

Specification of Letters Patent.

Patented Oct. 5, 1920.

Application filed July 27, 1918. Serial No. 247,062.

To all whom it may concern:

Be it known that I, CURTIS S. JORDAN, a citizen of the United States, residing at Los Angeles, in the county of Los Angeles and State of California, have invented a new and useful Timer, of which the following is a specification.

This invention pertains to devices of the character used for correctly timing the spark in internal combustion engines whereby ignition of the gases is effected in the different cylinders at the proper times, and an object of the invention is to make provision for the contact between the contact members continuing for relatively long intervals of time so as to insure the production of a "hot" spark.

Another object is to provide a device of this character in which wear may occur without the wear being detrimental to the making of contact between the contact members.

Other objects and advantages will appear from the subjoined detailed description.

The accompanying drawings illustrate the invention:

Figure 1 is an outer end elevation of a timer embodying the invention.

Fig. 2 is a plan section on line x^2-x^2 , Fig. 1.

Fig. 3 is a plan section on line x^3-x^3 , Fig. 1, portions of the rotative contact member being shown unsectioned.

Fig. 4 is a sectional elevation on line x^4-x^4 , Fig. 3.

Fig. 5 is a face view of the spring contact member support and the elements fastened thereto.

Fig. 6 is a sectional detail of the rotative contact members and a portion of the shaft on which they are mounted.

Fig. 7 is an enlarged detail of the upper end of the contact supporting member in Fig. 5.

Fig. 8 is a perspective view of one of the spring contact members.

Fig. 9 is a sectional elevation on line x^9-x^9 , Fig. 10, showing a modified form of the invention, the bearing for the housing being omitted.

Fig. 10 is an elevation mainly in section on line indicated by $x^{10}-x^{10}$, Fig. 9.

Fig. 11 is a sectional elevation analogous to Fig. 9 showing another form of the invention, the bearing for the housing being omitted.

Fig. 12 is a plan section on line $x^{12}-x^{12}$, Fig. 11.

Fig. 13 is a perspective view of one of the terminal blocks in Fig. 11. 60

Fig. 14 is an inverted plan view of the terminal shown in Fig. 13.

Fig. 15 is a perspective view of one of the spring-pressed contact members in Fig. 11. 65

The invention may be variously embodied and in the accompanying drawings several forms are illustrated. There is provided a bearing 1 which in the instance shown is in the form of a plate and substantially corresponds in general character to the bearing already in use for the timers on Ford cars as at present constructed. This bearing 1 is provided with an annular recess 2 in which is rotatively seated the flange 3 of a housing 4. The housing 4 is of any suitable shape and in the instance shown is provided at its outer end with a depression 5 which is adapted to be engaged by a spring arm a , Fig. 1, or other device designed to releasably hold the housing against the bearing 1. This spring arm a is well known as being used in connection with the Ford timer. 75

Projecting through a circular opening 6 in the bearing 1 and into the housing 4 is a shaft 7, only a portion of which is shown in the drawings. In Ford cars this shaft is the cam shaft and is driven in a well known manner. Of course the shaft 7 may be any suitably driven shaft and is rotatively supported in bearings, not shown, forming portions of the engine. 90

The shaft 7 is provided with a contact member 8 having any suitable number of contact points 9. In the instance shown the contact member 8 is cam-shaped and comprises a suitable number of cam-shaped rings 10, each ring including one of the contact points 9 mentioned above. The rings 10 are all fastened together by rivets 11 passing therethrough, said rivets all projecting through a washer 12 seated against the outermost face of the outer ring 10. The washer 12 is fastened in place by a pin 13 projecting from the shaft 7 and a cap 14 preferably fits over the periphery and outer face of the washer 12 so as to cover the outer end of the pin. On the outer end of the shaft 7 is a nut 15 seated against the cap 14 to hold said cap in place. 95

Preferably between the rings 10 are inserted spacing washers 16 to separate or space the cam rings 10 from one another. 110

The contact points 9, when the shaft 7 is rotated, are adapted to engage and make electrical contact with a corresponding number of spring-pressed contact members which 5 may be variously constructed. The drawings show several different constructions of these contact members and such constructions will be separately described.

Now referring more particularly to the 10 form of the invention shown in Figs. 1 to 8 inclusive, the spring-pressed contact members referred to above are shown at 17 and are in the form of flat faced leaf springs each provided with an angularly bent end 15 18. The ends 18 are seated in recesses 19 in one end of a support 20 which is made of suitable electrical insulating material. In contact with the bent ends 18 and seated in the recesses 19 are terminal blocks 21 20 through which pass screws 22, said screws also passing through the bent ends 18 and into the support 20 so as to firmly fasten the contact members 17 and blocks 21 in place. Leads 23 enter the blocks 21 and are fastened in place by binding screws 24. The leads 23 are adapted to connect with the spark plugs of the engine with which the timer is to be used. The support 20 is seated against insulation strips 25 which are 30 fastened to the flanges 25' by screws 26 or their equivalents.

The contact members 17 extend transversely of the axis of the shaft 7 and may be accommodated in grooves 27 formed in 35 the inner face of the support. Thus it is clear that the contact members 17 are well insulated from one another. The support 20 is mounted sufficiently close to the shaft 7 to insure that the contact points 9 will enter 40 the grooves 27 when making contact with the contact members 17.

The support 20 is detachably fastened to the housing 4 and for this purpose the housing is provided with an outstanding lip 28 45 which engages the outer face of the support. Thus the inner edge of the support 20 is embraced between the lip 28 and the insulation strips 25. The support 20 is provided with an ear 29 through which passes a stud 50 30 which projects from the housing 4. The outer end of the stud 30 is provided with a nut 31 seated against the ear 29 and screw-threaded onto said stud so as to be readily removed when it is desired to detach the 55 support 20 and the elements fastened to said support from the housing.

The housing 4 is cut away at one side at 6 to form an opening which is closed by the support 20.

60 In practice the form of the invention shown in Figs. 1 to 8 inclusive is operated as follows: The shaft 7 is turned at a correct rate of speed relative to the main engine shaft by any suitable driving connections between it and the main engine shaft,

and as the shaft 7 rotates it causes the contact points 9 to engage the contact members 17 respectively. As the contact points 9 are rotated they make a wiping contact for substantial distances with the flat faces or portions of the contact members 17, respectively, and owing to said contact members 17 being resilient they are first deflected by the contact points and then follow said contact points a certain distance so that intimate contact is maintained between the contact points 9 and contact members 17 for appreciable intervals of time, thus insuring a good flow of electric current to the spark plugs in order that while contact occurs between the contact points 9 and contact members 17 the spark plugs will produce relatively intense sparks.

It may be desirable to thicken the contact members 17 at the portions 32 thereof which are engaged by the contact points 9, so that they will endure considerable wear without it being necessary to replace them by others.

In the form of the invention shown in 90 Figs. 9 and 10 the spring-pressed contact members are in the form of reciprocative plungers 33 provided with stems 34 which pass through sleeves 35 mounted in a support 36 corresponding to the support 20 above described. The support 36 is detachably fastened to the housing 4 by the means described above for fastening the support 20 to the housing but by the nature of the views Figs. 9 and 10 the fastening means cannot be seen in detail and it is not necessary to 100 again illustrate and describe such fastening means.

The outer ends of the stems 34 are provided with heads 37 and seated against said heads are springs 38 which thus function 105 to tend to move the plungers 33 toward the contact points 9. The plungers 33 are accommodated in grooves 39.

The outer ends of the springs 38 rest against terminal blocks 40 which correspond 110 in some respects to the terminal blocks 21 above described. The blocks 40 are secured in place and leads 41 are secured to said blocks in the same manner as above described for the blocks 21 and leads 23.

115 In practice, the form of the invention shown in Figs. 9 and 10 operates the same as above described for the form of the invention shown in Figs. 1 to 8 inclusive excepting that the plungers 33 are first moved outward by the contact points 9 and are then moved back, to follow up the rotating contact points 9, by the springs 38. In this device the insulation strips 25 and screws 26 are seen and function the same as described 120 for Figs. 1 to 8.

Now considering more particularly the form of the invention disclosed in Figs. 11 to 15 inclusive, the spring-pressed contact members are in the form of nonresilient bars 130

42 pivoted at 43 to terminal blocks 44 which correspond to the terminal blocks 21 above described. Leads 45 are fastened to the blocks 44 as above described in connection with Figs. 1 to 8 and the blocks are fastened to a support 46 by screws 47. The blocks 44 are provided with recesses 48 in which are seated springs 49 which have one end resting against the outer faces of the contact members 42 so as to tend to press said contact members toward the contact points 9. The support 46 is similar to the support 20, being provided with grooves 50 corresponding to the above described grooves 27 to accommodate the contact members 42 and the tips of the contact points 9. This device is provided with the insulation strips 25 flanges 25' and screws 26 the same as in the form shown in Figs. 1 to 8.

20 The operation of the invention just described is clear from the description above of the form of the invention shown in Figs. 1 to 8, the only difference being that instead of the flexing of the contact members 17 by 25 the engaging therewith of the contact points 9, the springs 48 are compressed when the contact points 9 push the contact members 42 outward.

Advance and retardation of the spark 30 may be obtained by turning the housing 4 in the appropriate direction in the bearing 1 as is well understood in the art to which the invention pertains.

It is understood that other modifications 35 of the invention may be made without departing from the invention so long as such modifications lie within the spirit and scope of the appended claims.

I claim:

40 1. A timer comprising a housing cut away at one side to form an opening and provided with a flange and with a lip spaced from the flange, a rotative contact member in the housing, means to turn the contact member, a support of electric insulating material extending over the opening and provided with an ear and projecting in the space between the lip and flange, a stud on the housing projecting through the ear, a 45 nut screw-threaded on the stud and seated against the ear, and a contact member connected to the support and projecting into the path of travel of the first named contact member.

50 55 2. A timer comprising a housing, a shaft projecting into the housing, cam-shaped rings mounted on the shaft and rotative therewith, washers on the shaft interposed between adjacent rings, a support, and leaf 55 springs fastened to the support and engageable by the respective rings when the shaft is turned.

60 3. A timer comprising a housing having

an opening therein, a support of insulation fastened to the housing and projecting over 65 the opening and having recesses at one end, flat faced leaf springs having angularly bent ends seated in the recesses, terminal blocks in the recesses in contact with the bent ends of the leaf springs, screws passing through 70 the blocks and bent ends of the springs and into the support, a shaft projecting into the housing, and a contact member on the shaft having projecting points adapted to making wiping contact for substantial distances with 75 the flat faces of the leaf springs when the shaft is turned, the points being the only portions of the contact member to engage the leaf springs.

4. A timer comprising a housing, a shaft 80 projecting into the housing, cam-shaped rings mounted on the shaft and rotative therewith, washers on the shaft between the adjacent rings to space said rings from one another, a washer on the shaft seated against 85 the outer face of the outer ring, a pin fastening the last named washer to the shaft, a cap covering the periphery of the last named washer, a nut on the shaft seated against the cap, a support, and leaf springs 90 fastened to the support and engageable by the respective rings when the shaft is turned.

5. A timer comprising a housing having an opening therein, a support of insulation fastened to the housing and projecting over 95 the opening and having grooves in its inner face and having recesses at one end, flat faced leaf springs extending lengthwise in the grooves and having angularly bent ends seated in the recesses, terminal blocks in the 100 recesses in contact with the bent ends of the leaf springs, screws passing through the blocks and bent ends of the springs and into the support, a shaft projecting into the housing, and a contact member on the shaft having projecting points adapted to make wiping contact for substantial distances with the flat faces of the leaf springs when the shaft is turned, the contact points being the only portions of the contact member to engage 110 the leaf springs.

6. A timer comprising a housing, a shaft projecting into the housing, cam-shaped rings mounted on the shaft and rotative therewith, washers on the shaft interposed 115 between adjacent rings, a support, and electrical contact members mounted on the support and engageable by the respective rings when the shaft is turned, said contact members being yieldingly held toward said rings. 120

Signed at Los Angeles, California, this 20th day of July, 1918.
